DR D 11,312

No. 11,312

August 5, 1879

UNITED STATES PATENT OFFICE.

FREDERICK T. CHASE, OF WEBSTER, MASSACHUSETTS.

DESIGN FOR SCOTCH SUITINGS.

Specification forming part of Design No. 11,312, dated August 5, 1879; application filed May 20, 1879.
[Term of patent 3½ years.]

To all whom it may concern:

Be it known that I, FREDERICK T. CHASE, of Webster, in the county of Worcester and State of Massachusetts, have originated and designed a Pattern for Scotch Suitings or other Fabrics, of which the following is a full, clear, and exact description, reference being had to the accompanying photographic illustration, making part of this specification.

My design is formed in the weaving of the goods, which may be made of No. 2½ to No. 5½ double-and-twist yarn of suitable colors.

It consists in the arrangement of three bars, A, nearly forming a square, in rows, separated in the rows by a space, B, of about two-thirds the width of the bars. The rows alternate with those made by the three shorter bars C, between and at right angles to the others, the squares formed by which are separated by spaces, in which the diagonal bar D is placed.

None of the parts are very bold in appearance, but are changeable in different lights, by reason of some parts of the design not being apparent.

All except the bars C and D have a crimp appearance, giving the whole the effect of a crimp check with a diagonal cast.

What I claim as my invention is—

The design described, consisting of the two sets of bars A C, arranged as shown, with spaces between them filled with a varied weave having a crimp-like appearance, and the diagonal D, substantially as set forth.

FREDK. T. CHASE.
